WITNESS:

UNITED STATES PATENT OFFICE.

FRANCES P. SLOSSER, OF WASHINGTON, IOWA.

CARD HOLDER.

Application filed April 30, 1928. Serial No. 273,955.

This invention relates to card holders for holding and displaying cards containing reading matter of various kinds, the invention being especially useful as a holder for menu cards.

An object of the present invention is the provision of a card holder which will prevent the card from becoming soiled and mutilated through handling, and which will keep it in a sanitary and attractive condition, the material and construction of the holder being such as to permit of the said holder being frequently and readily cleaned, so that the holder may also be kept sanitary.

Another object of the invention is the provision of a holder which in addition to the above advantages, is constructed of elements and parts which are readily purchaseable and easily assembled, so that the holder may be manufactured at a nominal cost.

With the above and other objects in view, the invention further includes the following novel features and details of construction, to be hereinafter more fully described, illustrated in the accompanying drawing and pointed out in the appended claims.

In the drawing:—

Figure 1 is a perspective view illustrating the invention.

Figure 2 is a section showing the holder folded.

Referring to the drawing in detail wherein like characters of reference denote corresponding parts, the holder comprises one or more, preferably two pockets indicated generally at 10. These pockets are formed of flat sheets of transparent waterproof material 11 which are arranged in contacting relation and are connected around three of their edges so as to provide a pocket whose open end is indicated at 12.

The edges of the pocket are secured together by means of eyelets 13 and these eyelets are preferably white stainless fast color shoe eyelets and are likewise waterproof so that the entire pocket structure may be readily cleaned. The sheets of material preferably consist of celluloid or like flexible mate-

rial so that their inner faces normally contact throughout their entire areas, yet may be separated for the insertion of a card 14 and will grip the card in a manner to hold the same against accidental displacement even though the card is of thin cardboard, or paper. The cards may contain a restaurant or other menu and may also contain advertising matter, the cards shown displaying a soda fountain menu in addition to advertising matter.

Two or more pockets may be connected and for this purpose the eyelets 13 receive open rings 15, preferably of the type known as poultry rings or poultry markers and are also formed of a white stainless material which is waterproof. The holder will thus present a neat, attractive and sanitary appearance and as it may be readily washed or cleaned, it can be kept in such condition. In addition, it will protect the displayed card so that the latter will not become mutilated or soiled.

As the eyelets 13 extend around three sides of the pockets, any number of pockets may be assembled with the rings connecting the longitudinal edges of the pockets, or if desired, the rings may connect the closed ends of the pockets so that cards having longitudinally extending reading matter may be used if desired.

The invention is susceptible of various changes in its form, proportions and minor details of construction and the right is herein reserved to make such changes as properly fall within the scope of the appended claim.

Having described the invention what is claimed is:—

A card holder comprising a pair of card-receiving pockets, each formed of flat sheets of transparent waterproof material arranged in contacting relation and waterproof eyelets securing the sheets together along three of their edges, and open rings extending through the eyelets along adjacent edges of the pockets to hingedly connect said pockets.

In testimony whereof I affix my signature.

FRANCES P. SLOSSER.
